UNITED STATES PATENT OFFICE.

THOMAS J. CAHILL, OF PHILADELPHIA, PENNSYLVANIA.

AEROPLANE LANDING AND ARRESTING APPARATUS.

Application filed December 8, 1925. Serial No. 73,962.

This invention relates to aeroplane landing and arresting apparatus and its objects are to provide apparatus of comparatively simple construction which may be readily 5 constructed above the deck of a ship, on the roof of a building or in the field; by which the speed of a landing aeroplane may be gradually retarded and the aeroplane brought to rest within a short distance; 10 which may be adjusted to gradually bring the aeroplane to rest within any desired distance; which will always be set for arresting an aeroplane, and which will securely hold and serve as an anchorage for one or 15 more aeroplanes after arresting them.

These objects, and other advantageous ends which will be described hereinafter, I attain in the following manner, reference being had to the accompanying drawings 20 in which

Figure 1 is a plan view of an apparatus constructed in accordance with my invention showing an aeroplane thereon.

Figure 2 an enlarged fragmentary sectional plan view of the apparatus shown in Figure 1,

Figure 3 a section on line 3—3 of Figure 2,

Figure 4 a section on line 4—4 of Figure 2,

Figure 5 a section on line 5—5 of Figure 1,

Figure 6 a fragmentary side view of the aeroplane having an element of my invention secured thereto, and

Figure 7 a section on line 7—7 of Figure 6.

Referring to the drawings, 1 indicates an aeroplane, 2 a frictional member which may 40 be suspended from the aeroplane in any manner, and 3 an arresting and landing platform which when the aeroplane alights thereon, is slidably engaged by the frictional member 2. The friction produced between the platform and the frictional member gradually retards the speed of the aeroplane so that it comes to rest within a short distance after landing.

The frictional member 2, for simplicity, 50 and clearness of illustration, is shown as secured to the under side of the body of the aeroplane, but it will function equally well when pivotally or movably suspended from any other part of the aeroplane. The frictional member has a shank 4 and a laterally disposed plate 5 thereon with its advance

end 6 pointed, and the upper and lower faces of the plate tapered toward the point so that it will readily find its way under the overlapping plates of the platform. 60

The platform consists of a supporting plate 7 and a plurality of spaced series of overlapping plates 8 yieldingly secured thereto. The overlying end 9 of each overlapping plate is pointed and slightly bent 65 upwardly so that point 6, of the lateral plate, will readily slide under the overlapping plates, and the shank 4 will be guided into a guideway 10 formed by the spacing of the series of overlapping plates as shown in 70 Figures 1 and 2.

The overlapping plates 8 are yieldingly secured to supporting plate 7 by studs 11 depending from the overlapping plates and passing through the supporting plate, and coiled springs 12 interposed between the under side of the supporting plate and nuts 13 on the studs. The tension placed on the springs gradually increases from the landing end of the platform to the stopping end 80 as shown in Figure 5, so that the frictional force produced on the frictional member due to the pressing action of the overlapping plates, is gradually increased toward the 85 stopping end.

A platform of this type may be readily constructed above the deck of a ship, on the top of a building or in the field. An aeroplane about to alight on the platform is piloted to travel substantially parallel to the guideways 10 of the platform. When it lands, the frictional member 2 will engage the platform and its plate 5 will find its way under the pointed and upwardly bent ends 9 of the overlapping plates and between them into one of the guideways 10. As the frictional member slides under the overlapping plates, the frictional force produced will retard its speed and bring the aeroplane to rest. The frictional force is produced by coiled springs 12 tending to force the overlapping plates downwardly against the lateral plate 5. Having the tension of the springs gradually increased from the landing to the stopping end of the platform, 95 produces a frictional force which will gradually stop the aeroplane within a comparatively short distance. This frictional force may be varied by turning nuts 13 so as to bring the aeroplane to rest within any desired distance. After the aeroplane has come to rest, the frictional member 2 will be 100 105 110

held tightly under the overlapping plates 8 and will thus anchor the aeroplane to the platform.

It will be seen that the landing and resting platform above set forth will always be set for arresting an aeroplane, and thus avoid the necessity of resetting the apparatus after an aeroplane makes a landing, as is required of the old arresting apparatus now in use.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. Apparatus for arresting aeroplanes including a frictional sliding member adapted to be suspended from the aeroplane; a support, and a plurality of spaced series of overlapping plates yieldingly secured to the support, the overlying end of each plate being formed to guide the member under and between a pair of said series of plates.

2. Apparatus for arresting aeroplanes including a frictional sliding member adapted to be suspended from the aeroplane; a support and a plurality of spaced series of overlapping plates yieldingly secured to the support, the overlying end of each plate being pointed and bent upwardly to guide the member under and between a pair of said series of plates.

3. Apparatus for arresting aeroplanes including a frictional sliding member adapted to be suspended from the aeroplane; a supporting plate; a plurality of spaced series of

overlapping plates; studs secured to the overlapping plates and passing through the supporting plate, and resilient means for connecting the studs to the supporting plate, the overlying ends of the overlapping plates being formed to guide the member under and between a pair of said series of plates.

4. Apparatus for arresting aeroplanes including a frictional sliding member adapted to be suspended from the aeroplane; a supporting plate; a plurality of spaced series of overlapping plates; studs secured to the overlapping plates and passing through the supporting plate; springs on the studs, and adjusting members on the studs for compressing the springs against the supporting plate, the overlying ends of the overlapping plates being formed to guide the member under and between a pair of said series of plates.

5. Apparatus for arresting aeroplanes including a frictional sliding member adapted to be suspended from the aeroplane, said member having a laterally disposed plate; a support, and a plurality of spaced series of overlapping plates yieldingly secured to the support, the overlying ends of the plates being formed to guide the laterally disposed plate under the overlapping plates.

6. Apparatus for arresting aeroplanes including a frictional sliding member adapted to be suspended from the aeroplane, said member having a laterally disposed plate with its advance end pointed; a support, and a plurality of spaced series of overlapping plates yieldingly secured to the support, the overlying ends of the plates being formed to guide the laterally disposed plate under the overlapping plates.

In testimony whereof I have signed my name to this specification.

THOMAS J. CAHILL.
